FOLDING FINS FOR ROCKETS AND MISSILES

Albert S. Gould, Inyokern, Calif.

Application February 6, 1953, Serial No. 335,615

4 Claims. (Cl. 102—50)

(Granted under Title 35, U. S. Code (1952), sec. 266)

The invention described herein may be manufactured and used by or for the Government of the United States of America for governmental purposes without the payment of any royalties thereon or therefor.

This invention relates to rockets and more particularly to improvements in stabilizing fins for same.

One of the objects of the invention is to provide a novel multiple fin construction for a rocket which permits launching of the rocket through a launching tube with the fins in folded position.

Another object is to provide a novel folding fin and exhaust nozzle construction.

Another object is to provide novel mechanism for jointly actuating the fins to their extended positions, utilizing the pressure in the rocket motor reaction chamber.

Another object is to actuate the fins to their extended positions by a fin opening force resisting an acceleration force, both of which are proportional to the rocket motor reaction chamber pressure.

Another object is to provide a folding fin construction which may be readily employed in rockets of relatively small calibre.

Another object is to provide a simplified folding fin construction which may be economically mass produced.

Other objects and many of the attendant advantages of this invention will be readily appreciated as the same becomes better understood by reference to the following detailed description when considered in connection with the accompanying drawings wherein:

Fig. 1 is a longitudinal cross section of one form of rocket nozzle and fin construction, showing the fins in folded position, taken on line 1—1, Figs. 3 and 4, portions being broken away and other portions omitted;

Fig. 1A is a fragmentary view similar to Fig. 1, showing the fins in extended position;

Fig. 2 is a section taken on line 2—2, Fig. 1;

Fig. 3 is a rear elevation as viewed from plane 3—3, Fig. 1, a portion being broken away;

Fig. 4 is an enlarged side elevation of a detail, viewed in the direction of arrow 4, Fig. 1;

Fig. 5 is a section taken on line 5—5, Fig. 1;

Fig. 6 is a section taken on line 6—6, Fig. 1;

Fig. 7 is an enlarged side elevation of a fin retainer shown in Fig. 1;

Fig. 8 is a rear elevation of Fig. 7, as viewed in the direction of arrow 8;

Fig. 9 is a section taken on line 9—9, Fig. 8, showing the retainer associated with fragments of the fins, portions of the latter being broken away;

Fig. 10 is a rear elevation of an alternative form of the invention;

Fig. 11 is a fragmentary section taken on line 11—11, showing a fin in folded position, and

Fig. 11A is a section like Fig. 11, showing a fin in extended position.

Referring in detail to the drawing, and particularly Figs. 1 to 9, the subject of the invention comprises a

cup-shaped member 20 which is secured to the rear end of a rocket motor tube 22 in any suitable manner, this member forming the rear closure for the rocket motor and also a support for a plurality of angularly spaced nozzles 24, 24a, 24b, 24c. A collar 26 is secured to member 20 by a plurality of screws 28 and is provided with equiangularly spaced slots 30, 30a, 30b, 30c which receive, respectively, the base portions, 32, 32a, 32b, 32c of fins 34, 34a, 34b, 34c. As best shown in Figs. 1, 2 and 4, a pin 36, supported in aperture in member 26 and extending through an aperture in base portion 32 of fin 34, pivotally supports the latter on the rocket for movement in a plane passing through the longitudinal axis of the rocket. As will be apparent, fins 34a, 34b, 34c are pivotally connected to member 26 in the same manner by pins 36a, 36b, 36c, respectively.

A cylinder 38 is rigidly affixed to the center of member 20 and slideably carries a piston 40 therein to one end of which is rigidly affixed a cruciform member 42 having projecting fingers 43, 43a, 43b, 43c. As best shown in Fig. 2, member 42 is shaped so that it may slide in the spaces between the various nozzles. A cap 44 having apertures 46 extending therethrough is disposed on the inner end of the cylinder. The piston is provided with a frustoconical portion 48 and the cylinder is provided with a bore 50 of similar shape, the purpose of which will subsequently appear.

The fins are of uniform width and uniformly decrease in thickness from their forward or base portions toward their rear or tip ends. The side faces are beveled so that the leading and trailing edges are generally knife shaped. As best shown in Fig. 5, the base portion of each fin is provided with a thinned portion 52 which may be disposed in the space between adjacent nozzles. The front surface of this portion forms a camming abutment against which an associated projecting finger of member 42 may engage.

As best shown in Figs. 1, 7, 8 and 9, the fins are provided with notches 54 which receive a resilient circular wire member 56 which is disposed in a circular groove 58 in a fin retainer member 60. This member is also provided with four equiangularly spaced notches 62, each of which receives a rear portion of a fin tip. As best shown in Figs. 1 and 6, a notched rubber disk 64 is disposed between the various fins and urges them outwardly, this urge being resisted by wire 56, engaging in notches 54, thus preventing unauthorized outward movement of the fins. Member 60 is constructed of electrical insulating material and is provided with a metallic contact 66. One end of a lead wire 68 is connected to this contact, the lead wire being trained through an aperture 70 in member 64 and thence through one of the nozzles where its other end (not shown) connects with one end of a bridge wire of a squib disposed within the rocket motor, the other end of the bridge wire being grounded to the motor.

In the operation of the invention so far described, the rocket is disposed within a launcher tube which is slightly larger in diameter than the rocket. When the rocket is to be launched an electrical potential is applied between contact 66 and the rocket tube which causes current to flow through the bridge wire of the squib firing the latter and igniting the propellant charge in the rocket motor. The nozzle blast blows away fin retainer 60, and the pressure in the motor forces piston 40 and member 42 rearwardly thus tending to cam the fins outwardly. The tube, however, restrains this motion and the fins ride against the tube until the rocket has passed through its forward end. At this point, with the tube restraint no longer present, the piston moves to its rearward limit position, as shown in Fig. 1A, actuating the fins to their outward flight positions. Tapered portion 48 of the piston jams and locks in tapered bore 50, preventing retrograde move-

ment of the piston during rocket decelerations. The fins are retained in their flight position, as shown in Fig. 1A, during rocket acceleration, since they tend to return to their folded position under urge of acceleration and aerodynamic drag forces. During rocket deceleration they still retain this position due to aerodynamic drag thereon.

The construction illustrated in Figs. 10, 11, 11A is in all essential respects the same as that previously described, the principal difference being in the manner in which the fins are cammed to open position. In the construction so far described the rear surface 45 of a finger of member 42 engages surface 47 on a fin forcing the latter outwardly until the parts move to the position shown in Fig. 1A wherein corner 49 of a fin engages the outer surface 51 of the finger. With this construction, the lever arm acting to rotate the fin is relatively short. In the construction shown in Figs. 10, 11 and 11A, a fin contacts member 142 at a greater distance from the pivotal axis of the fin and hence the lever arm acting to rotate the fin is considerably greater. As the fin is moved outward and its initial inertia overcome, the camming action continues in a manner similar to the first described embodiment, that is, with a relatively shorter lever arm. When the parts reach the position shown in Fig. 11A, the outer tip of a finger is disposed in a notch 135 of a fin which latches the parts against retrograde movement.

Obviously many modifications and variations of the present invention are possible in the light of the above teachings. It is therefore to be understood that within the scope of the appended claims the invention may be practiced otherwise than as specifically described.

What is claimed is:

1. In a rocket motor a cup shaped closure member adapted to be secured to the rear end of said rocket and having a rear wall, said closure member having exit means for the discharge of propellant gases from said rocket, a plurality of fins pivotally mounted on the rear wall of said closure member for angular rotation from a rearwardly folded position to a forwardly open position, each of said fins having an exposed lateral surface on the forward end thereof, and an actuator for said pivotally mounted fins interposed between the end wall of said closure member and the lateral end surface of each of said fins for abutting engagement therewith, and means operated by the internal gas pressure of said rocket motor for transmitting longitudinal movement to said actuator, the said actuator having slideable abutting engagement with the end surface of said fins whereby to cause the angular rotation of said fins about said pivot to decrease with the longitudinal movement of said actuator.

2. In a foldable fin stabilized rocket, a cup shaped member adapted to be secured to the rear end of said rocket and having a rear wall, a plurality of exhaust noz-

zles formed in said rear wall and projecting rearwardly therefrom, a piston mounted in a cylinder formed integrally with the rear wall of said closure member and extending forwardly therefrom, said piston being movable in said cylinder by gas pressure within the rocket motor and having a portion thereof extending rearwardly through said rear wall, a plurality of outwardly radially projecting fingers each secured to said extending portion of said piston for actuating said fins, said fingers being in interdigital relation with the projecting portions of said nozzles, each of said fingers having a lateral rearwardly exposed surface and terminating in an outer end surface substantially equidistant from the longitudinal axis of said piston, the said end surface forming a camming corner with the lateral rearwardly exposed surface of said finger, a plurality of substantially rectangularly shaped fins corresponding in numbers to said fingers, means pivotally mounting each of said fins to the rear wall of said closure member at the outer forward corner thereof, each fin having a forwardly facing surface in abutting relation with the said lateral surface of a respective one of said fingers, the forwardly facing surface of said fins being adapted to be slidably and cammingly engaged by said camming corner whereby the angular rotation of said fins decreases with the linear rearward movement of said fingers in rotating said fins about said pivot from a rearwardly folded position to a forwardly open position.

3. The combination described in claim 2 above wherein the forwardly facing surface of each of said fins terminates at its inner end in a heel adapted to be engaged by the outer end surface of said finger near the end of travel thereof to lock said fins against retrograde movement during the flight of said rocket.

4. The combination described in claim 3, wherein said piston is further modified by the addition of means for jamming the piston in the cylinder when the piston has moved to the rearward limit of its motion.
